Patented Aug. 1, 1922.

Inventor:

George G. Bush,
by
J. L. Moore,
his attorney.

UNITED STATES PATENT OFFICE.

GEORGE G. BUSH, OF BRISTOL, CONNECTICUT.

POLISHER.

1,424,448.

Specification of Letters Patent.

Patented Aug. 1, 1922.

Application filed May 20, 1921. Serial No. 471,063.

To all whom it may concern:

Be it known that I, GEORGE G. BUSH, a citizen of the United States, residing at Bristol, county of Hartford, State of Connecticut, have invented a certain new and useful Polisher, of which the following is a full, clear, and exact description, such as will enable others skilled in the art to which it appertains to make and use the same, reference being had to the accompanying drawings, forming part of this specification.

My invention relates to improvements in polishers, such, for example, as for polishing shoes, my object being to provide a structure which can be easily and inexpensively made, and can also be efficiently and conveniently manipulated. To this end, and also to improve generally upon devices of the character indicated, my invention consists in the various matters hereinafter described and claimed.

In the accompanying drawings: Figure 1 is a top plan; Figure 2 is a side elevation, the yoke being also shown in dotted lines in position to permit the removal of a cloth; and Figure 3 is a side elevation showing the method of attaching a cloth.

Referring now more particularly to these drawings, 1 indicates a base or body portion, which may conveniently be a block of wood, and this body portion has its ends provided with transverse channels of generally V-shape to produce beads 2 across the upper edges and lower projecting portions 35 11, the transverse edges of the lower portions being preferably rounded as at 3, and each of the end surfaces of the block slanting inwardly from the outer edge of the bead and the outer, rounded edge of the 40 lower projection until they meet each other. A pad 4 of relatively soft, yielding material, as felt, extends along the bottom of the base and around the ends thereof to the bottoms of the before-mentioned notches, 45 where the pad-ends are suitably permanently secured to the block, as by tacks 5.

A yoke is provided which is separable from the block and consists of two substantially U-shaped portions each of which has 50 a transverse end bar 6 and side bars 7, the bars upon each side being connected by coiled springs 8 whose ends are suitably fastened to the bars which they connect. A removable polishing cloth 9 is stretched over 55 the pad 4 and has its ends brought up along the pad-covered ends of the base and there

held in position by the end bars 6 of the resilient yoke, these end bars lying in the channelled ends of the block 1 and clamping the cloth against the felt pad which covers the block-ends to lines beneath the yoke-bars 6 when the latter are in the final, securing position, so that this felt forms a yielding backing into which the cloth ends can be pulled by the yoke bars and thus firmly held. Each end bar 6 of the yoke pressing into the pad as just explained and lying beneath a bead 2 and above the outwardly slanting lower portion of the block, and these yoke portions being held under tension in such position by the springs 8, the yoke and cloth are well secured upon the block against accidental displacement.

By grasping the block in the hand the shoe or other article can be polished by brushing, as will be well understood, the cloth rubbing against the article being acted upon and the springs 8 affording slightly roughened surfaces which assist the user's grip upon the polisher. To remove the cloth it is only necessary to hold the polisher in one hand and with the other hand pull downwardly upon an end of the cloth, as the end 10, whereupon, the spring 8 allowing the yoke to elongate, that end of the yoke adjacent the cloth-end being pulled will slip over the lower edge of the polisher-end, as indicated in dotted lines in Figure 2, and the cloth will be free. To attach a cloth, one end of it (as the left hand one) 90 is caught by the corresponding transverse bar of the bail, as shown in Figure 3, and, the bail then being placed to extend upwardly so that its other transverse bar is above the block 1, the cloth is carried along the bottom of the pad and its free end then threaded over the said upper transverse bar of the bail, all as indicated in Figure 3, whereupon a downward pull upon this free end, 10, of the cloth will not only draw the cloth taut over the pad but will also pull the bail-end down until its transverse bar passes over the right hand bead 2 and snaps into the securing position shown by full lines in Figure 2.

Thus, the present polisher is of extremely simple and inexpensive construction, provides a permanent, yielding, soft pad which can yield to the shoe, or other article, for efficient polishing and yet is covered to prevent wear of the pad, affords a renewable cloth for contact with the article being pol-

ished, and provides for easy and simple removal and attachment of such cloth, thus making it convenient not only to renew a cloth when worn but also to use different cloths for polish of different color while the same block and soft pad are employed at all times.

I claim:

1. In a polisher or the like, a base, a removable rubbing element thereon, and a clamp having end portions clamping said rubbing element to said base, said end portions being connected by coiled springs which extend along the sides of said base in an exposed position, whereby said springs afford roughened surfaces which can be grasped by the hand of the user when using said polisher; substantially as described.
2. In a device of the character indicated, a base having beads at its ends, a pad on said base having end portions adjacent the under side of said beads and extending outwardly therefrom, a rubbing element on said base and having portions over the pad at its said end portions, and a clamp hav-

ing portions clamping said rubbing element between said beads and the respective neighboring end portions of the pad; substantially as described.

3. A polisher or the like comprising a base block having substantially straight sides and also having beads at its ends, said block extending outwardly at said ends below said beads, a yielding pad secured to said block, said pad extending along the bottom and the ends of said block and having its ends abutting against said beads, a removable rubbing element extending over said pad, and a clamp having end portions below said beads and there clamping said rubbing element against said pad, said clamp also having coiled springs connected to said end portions and extending along said substantially straight sides of said block and there exposed to the grasp of the operator; substantially as described.

In testimony whereof I hereunto affix my signature.

GEORGE G. BUSH.
